UNITED STATES PATENT OFFICE.

FRED H. BAILEY, OF LEOMINSTER, MASSACHUSETTS.

ATTACHMENT FOR FIRE-EXTINGUISHERS.

SPECIFICATION forming part of Letters Patent No. 783,499, dated February 28, 1905.

Application filed April 18, 1904. Serial No. 203,554.

To all whom it may concern:

Be it known that I, FRED H. BAILEY, of Leominster, in the county of Worcester and State of Massachusetts, have invented certain new and useful Improvements in Attachments for Fire-Extinguishers; and I do hereby declare that the following is a full, clear, and exact description of the same.

This invention relates to fire-extinguishers, and particularly to that class in which a receptacle is overturned in order to cause a commingling of the charging agent with the liquid contained in the receptacle.

An object of this invention is to provide a fire-extinguisher suitably suspended and held against action through the medium of a fusible retaining device, which being destroyed by heat occasioned by a fire will release the receptacle and cause a discharge of the liquid contained therein.

Furthermore, an object of the invention is to provide novel means whereby the fusible retaining device is utilized, making this invention applicable to this class of extinguishers now in use.

Furthermore, an object of this invention is to provide novel means for utilizing the overturning or partial rotation of the receptacle as a means for causing an alarm to be sounded when the receptacle is released.

Finally, an object of the invention is to provide an extinguisher of the character noted which will possess advantages in efficiency and durability proving comparatively inexpensive to manufacture and maintain.

With the foregoing and other objects in view the invention consists in the details of construction and in the arrangement and combination of parts to be hereinafter more fully set forth and specifically claimed.

In describing the invention in detail reference will be had to the accompanying drawings, forming part of this specification, wherein like characters denote corresponding parts throughout the several views, in which—

Figure 1 is a view in elevation illustrating a receptacle suitably suspended and held in its inoperative position through the medium of the fusible coupling. Fig. 2 is a perspec-

tive view of the attachment capable of being applied to extinguishers now in common use.

In the drawings, 1 indicates the tank containing the water and the agent to be mixed with the water when the receptacle is inverted, and 2 are trunnions projecting from opposite sides of the receptacle and adapted to support the receptacle, the said trunnions being engaged by the hanger 3, having holes 4 for the reception of the trunnions. The hanger 3 has a yoke-like structure having a horizontally-disposed member and two depending members in which the trunnions are journaled. The portion 5 of the hanger extends a distance below the opposite member and terminates approximately on line with the bottom of the receptacle when said receptacle is standing upright. The arm 6 is slidable in a loop or keeper 7, arranged on the bottom of the receptacle, the said arm having its end bent at an angle to the arm proper as shown at 8, the said extension being placed to lie parallel with the lower portion of the member 5. A retaining-band A, of fusible material, is slidable on the lower portion of the member 5 and is adapted to engage the end 8 of the arm 6, as shown in Fig. 1, whereby rotation of the receptacle is prevented so long as the band A remains intact.

The hanger is suspended from the ceiling or from any other suitable object and is attached thereto by means of screws *a*, which are run through apertures *a'* in the horizontal portion of the said hanger. When the parts are assembled in the relation shown in Fig. 1 and stationed at a place where there is danger of fire, should a fire occur the band A will be destroyed when the heat has reached a predetermined temperature, thus allowing the trunnions of the receptacle to rotate and causing the said receptacle to upset, bringing the perforated head B down and permitting the contents of the receptacle to be sprinkled over the surface of the floor. Owing to the construction of the sprinkler there will be considerable divergence of the spray. As a further means for safeguarding the premises I utilize, in connection with the receptacle and the hanger, a signaling device whereby when the

receptacle upsets an alarm is sounded by means of a contact C, here shown in the form of a small bracket attached to the side of the receptacle, which is positioned thereon 5 contact with a push-button D or other device for closing the electric current, which may flow over the conductor E to any suitable alarm. (Not shown.) As it is not my purpose to be limited to any particular alarm system or 10 means for causing the signal to be given, the said alarm need not, it is thought, be described in detail.

The construction, operation, and advantages will, it is thought, be understood from the 15 foregoing description, it being noted that various changes may be resorted to in the proportions and details of construction for successfully carrying the invention into practice without departing from the scope thereof.

20 Having fully described the invention, what I claim as new, and desire to secure by Letters Patent, is—

1. In a fire-extinguishing device, a receptacle, trunnions on the receptacle, a yoke in 25 which the trunnions are mounted, an extension on one of arms of the yoke, a keeper on

the bottom of the receptacle, an arm slideable in the keeper, and a fusible connection between the extension of the yoke and the slideable arm.

2. In a fire-extinguishing device, a yoke, securing means on the yoke, a receptacle pivoted between the arms of the yoke, an extension on one of the arms of the yoke, an arm slideably secured to the bottom of the receptacle, one end of the arm being turned upward a portion of its length parallel with the extension of the yoke, and a fusible slide on the extension adapted to embrace the upturned portion of the arm. 30

3. In a fire-extinguishing device, a yoke, a receptacle pivoted therein, a sliding arm on the bottom of the receptacle, a fusible connection between said sliding arm and one of the arms of the yoke below the pivotal point 45 of the receptacle and a signal means carried by the yoke above the pivotal point of the receptacle. 40
